United States Patent

Des. 237,474
Patented Nov. 4, 1975

237,474

PALLET

Robert L. Tate, 2209C E. Santa Clara,
Santa Ana, Calif. 92705

Filed Aug. 15, 1974, Ser. No. 497,826

Term of patent 7 years

Int. Cl. D9—99

U.S. Cl. D12—53

FIG. 1.

FIG. 2.

FIG. 3.

FIG. 4.

FIG. 1 is a perspective view showing the top, front and right side of the pallet;

FIG. 2 is a right side elevational view thereof, the left side being a mirror image of the right side shown herein;

FIG. 3 is a rear elevational view thereof; and

FIG. 4 is a bottom plan view thereof.

I claim:

The ornamental design for a pallet, as shown.
